UNITED STATES PATENT OFFICE.

WILLARD E. SWIFT, OF WORCESTER, MASSACHUSETTS, ASSIGNOR TO UNITED STATES ENVELOPE COMPANY, OF SPRINGFIELD, MASSACHUSETTS, A CORPORATION OF MAINE.

TOILET-PAPER FIXTURE.

Application filed December 24, 1923. Serial No. 682,431.

My invention relates to toilet paper fixtures of the type in which a package of paper is carried by a pivotally mounted carrier or core that is permitted to be turned through 5 only a part of a revolution in order to remove a sheet of paper from the package.

A fixture of the above mentioned type is shown and described in United States Patent No. 498,900, issued June 6, 1893, to O. H. 10 Hicks, and this fixture is characterized by the provision of a projection on the pivoted core, or carrier, which is adapted to be received in a correspondingly shaped notch provided in the package of paper, when it is placed on 15 the core. The purpose of the coacting projection and notch on the core and paper, respectively, is to provide for the proper positioning of the package on the core, so that the end of the package which is perforated for 20 the severance of the sheets, will be held up- permost when the fixture is in its normal position. When placing a new package on the core of a fixture of this type, it not infrequently happens that a careless user reverses 25 the package when applying it to the core, so that its projection enters the tearing slit on one edge of the package instead of the notch. When this occurs, it is practically impossible to force the package all the way on the core, 30 so that one edge of the package will bind against one arm of the fixture and prevent its free turning movement. When once the core is locked in position with a package thereon, it cannot be unlocked until the package is ex- 35 hausted, thereby making it necessary to cut off and destroy an improperly positioned package.

By the present invention, I provide an im- 40 proved toilet paper fixture of the above indi- cated type that is characterized by the pro- vision of means whereby an improved form of package can ordinarily be received on the core of the fixture in only its proper position, so that when the core is locked, the edges of 45 the package will be positively maintained free of the fixture, and the package may al- ways be turned freely. None the less, if a package is inadvertently placed on the fixture in the wrong position, it will still be 50 possible to force it on all the way, so that the fixture may turn. In other words, I eliminate the unfortunate condition referred to, when the package cannot be forced on, nor the fixture turned, nor the package re-

moved, without destruction. My invention 55 further contemplates an improved fixture that is adapted to present a package of paper in the form of a roll, which will deliver only one sheet of paper at each removal. The above and other advantageous features of my invention will hereinafter more fully appear, reference being had to the accompanying drawings, in which—

Fig. 1 is a perspective view of a fixture 60 embodying my invention.

Fig. 2 is a perspective view of a toilet paper package adapted for use with the fixture shown in Fig. 1.

Fig. 3 is a view in front elevation of the fixture shown in Fig. 1, with the roll applied 70 thereto.

Fig. 4 is a fragmentary view, showing on a reduced scale, a sheet of paper that has been removed from the fixture shown in Fig. 3.

Fig. 5 is a perspective view of a fixture 75 adapted to present a paper package in the form of a roll.

Fig. 6 is a perspective view of a package 80 adapted to be received on the fixture shown in Fig. 5.

Fig. 7 is a view in front elevation of the fixture shown in Fig. 5, with a package ap- plied thereto.

Like reference characters refer to like parts 85 in the different figures.

Referring first to Figs. 1 and 3, the fixture comprises a body portion 1 adapted to be secured to a wall, or other support, with for- 90 wardly extending arms 2 and 3. A core for carrying the paper package between the arms is generally designated at 4, and is provided at one end with an axial pivot pin 5, which is received in a slot 6 provided in the end portion of the arm 3. A vertical pivot pin 7 extends through the axial pivot pin 5, so that the core is adapted for rotational move- 95 ment about its longitudinal axis, and for piv- otal movement about the vertical axis on the arm 3.

The other end of the core 4 is provided with a sleeve 8, within which is slidably mounted a locking pin 9 which is adapted to be yield- 100 ingly maintained in a socket 10 provided in the arm 2. The axis of the locking pin 9 is substantially in alignment with the axis of the pivot pin 5, so that when the end of the pin 9 is received in the socket 10, the core

4 is adapted for rotational movement between the arms 2 and 3. The lower portion of the core 4 is eccentrically weighted, as indicated at 11, so that when the pin 9 is received in 5 the socket 10, that portion of the core 4 above the pivotal axis, leans forward, as shown in Fig. 1. A cam 12 is provided at the end of the core adjacent the pivot pin 5, which cam is adapted to coact with a spring 13 so as 10 to check rotation of the core in opposite directions, so that it may be freely turned through only about one-half of a complete revolution. The exact form of the cam 12 forms no part of the present invention, but 15 is fully shown and described in the above mentioned Patent No. 498,900.

The core 4 is further provided with wedge shaped projections 14 and 15 which are located at diametrically opposite points on the 20 edges of the core with respect to its pivotal axis. The projection 14 is considerably thicker and longer than the projection 15, as clearly shown in Fig. 3, and the wedge 14 is always uppermost when the core 4 is pivotally supported between the arms 2 and 3. Referring now to Fig. 2, there is shown in perspective, a package 16 of paper which is to be received by the core 4, the package 16 being 25 in the form of a flattened oval. The package 16 is provided along one edge with perforations 17 of any desired form, and a notch 18, corresponding in form to the wedge 14, is provided in line with the perforations 17. The other edge of the package 16 is provided 30 with a notch 19 corresponding in form to the wedge 15. The package 16 also bears a label 20 having instructions printed thereon for the positioning of the package on the core 4, as will now be described.

40 When it is desired to place a new package 16 on the fixture shown in Fig. 1, the locking pin 9 is pulled out of the socket 10, thereby allowing the core 4 to be swung outwardly about the vertical pivot pin 7. The package 45 16 is then placed on the core 4 with its notched end first, so that the wedges 14 and 15 may enter the notches 18 and 19, respectively, as the package is slipped onto the core. As previously stated, the label 20 is provided with 50 the necessary instructions for the proper positioning of a package and in order to further simplify the operation, the word "Front" is printed plainly on the label 20. It will be apparent from an inspection of Figs. 1 and 2 55 that if the word "Front" is kept toward the user when placing the package 20 on the core 4, the notch 18 will be kept uppermost and so will properly register with the wedge 14. If, however, a careless user should ignore the 60 instructions and attempt to place the package on the core with the label away from him, then it will be impossible to push the package all the way onto the core, by reason of the fact that the large wedge 14 will not fit the small 65 notch 19. Unless the package 16 is all the

way on the core 4, it will be impossible to swing the core back into locking position between the arms 2 and 3, and the user will have to reverse the package so that the wedges will register with the proper notches. 70

Assuming that the user has placed the package 16 properly on the core, so that the wedges 14 and 15 are received in their respective notches 18 or 19, the core 4 is then swung into position between the arms 2 and 3, whereupon 75 the end of the pin 9 enters its socket 10. The core then will be positively locked in position so that it cannot be again moved from between the arms until the package is exhausted, or otherwise removed therefrom. As clearly 80 shown in Figs. 1 and 3, the core 4, with the package 16 thereon, normally hangs with the perforations 17 uppermost and inclined toward the user, the loose end of the paper extending downwardly between the arms 2 and 3, so that it may be readily seized. When the paper is pulled downwardly, the core is free 85 to turn through about one-half of a revolution, whereupon the spring 13 engages the cam 12 to prevent further movement of the core. When this occurs, a sheet of paper is detached at the perforations 17, whereupon 90 the core 4 and the package swing back to their normal position, with the perforations uppermost. After the core has been locked in 95 position, the package 16 is positively maintained in proper position thereon, by reason of the fact that both wedges 14 and 15 serve to prevent the package from creeping or slipping on the core either laterally or around the 100 same. In addition, the wedges 14 and 15 insure that the edges of the package 16 are held straight, so that there is no possibility of the package 16 jamming between the arms 2 and 105 3 when the core is turned by the act of removing a sheet of paper. A single sheet of paper, detached from the package, is illustrated in Fig. 4, from which it is apparent that the notch 19 provides a guide for folding the sheet at its middle. 110

Referring now to Figs. 5, 6 and 7, there is shown a modified form of fixture which is adapted to maintain a package of paper in the form of a roll. The fixture in this case comprises the usual base 21, with forwardly 115 extending arms 22 and 23, between which is pivotally mounted a core, generally indicated at 24. The core 24 comprises spaced circular plates 25 and 26 connected by a weighted portion 27 and a bar 28. The end of the core adjacent the plate 26 is pivotally connected to the arm 23 by means of horizontal and vertical pivot pins 29 and 30, respectively, in the same manner as the above described core 4. The other end of the core 24 is provided with 120 a locking pin 31 which is adapted to be received in a suitable socket 32 provided in the arm 33, so as to maintain the core 24 in position. 125

The plate 26 is provided with wedge shaped 130

projections 33 and 34 which are located at diametrically opposite points thereon, the wedge 33 being longer and wider than the wedge 34. When the core 24 is freely supported between the arms 22 and 23, the weighted portion 27 causes it to assume such a position that the wedge 33 will be uppermost and slightly inclined forward, as clearly shown in Fig. 5. The plate 26 also carries a cam or stop 35 which is adapted to coact with a spring 36 to limit turning movement of the core 24 in either direction of rotation, in substantially the same manner as the spring 13 coacts with the stop 12 on the core 4.

Referring now to Fig. 6, there is shown a paper package 37 which is to be received by the core 24, the package 37 being in the form of a flattened oval. The package 37 is provided along one edge with perforations 38 of any desired form, and a notch 39, corresponding in form to the wedge 33, is provided in line with the perforations 38. The other edge of the package 37 is provided with a notch 40 corresponding in form to the wedge 34. The package 37 also bears a label 41 having instructions thereon for placing the package on the core 24.

When it is desired to place a new package 37 on the empty core, the locking pin 31 is withdrawn from its socket 32, thereby allowing the core to be swung outwardly about the vertical pivot pin 30. The package 37 is then compressed at its ends to cause it to open up and assume a generally cylindrical form, after which it is placed on the core 24 with its notched end first, so that the wedges 33 and 34 may enter the notches 39 and 40, respectively. The label 41 has the word "Front" printed thereon in the same manner as the package 16, so that if the word "Front" is kept toward the user, the notch 39 will be uppermost and so register with the wedge 33. If, however, a careless user should attempt to place the package 37 on the core with the label away from him, then it will be impossible to push the package 37 all the way onto the core, by reason of the fact that the large wedge 33 will not fit the small notch 40. Unless the package 37 is all the way on the core 24, it will be impossible to swing the core into its locking position between the arms 22 and 23, and the user will have to reverse the package and put it on properly.

Assuming that the package 37 has been properly positioned on the core 24, the latter may then be locked into position and will hang freely between the arms of the fixture, with the perforations 38 uppermost, the free end of the paper then hanging downwardly, so that it may be readily seized. The package 37 will then be presented to the user in the

form of a roll, and it will only be possible to remove the paper one sheet at a time, by reason of the fact that the core 24 is permitted to make substantially only one-half of a revolution. A further advantage of my improved construction lies in the fact that the packages which are held in roll form on the fixture may be shipped in the form of flattened ovals, as shown in Fig. 6, which results in a great saving of space and cost of transportation.

From the foregoing, it is apparent that by my invention I have provided an improved form of fixture and a package therefor which can be received on the fixture in only one position, by reason of the provision of coacting projecting and recessed portions of different depths. It is practically impossible to place my improved package on a core, in a reversed position, because the lower projection would engage the uncut end of the package and allow the upper projection to enter only partially into the tearing slit. In this important feature, my package and fixture differ materially from the above mentioned patented fixture, on which it is possible to force a package with the projection received in the tearing slit, as previously pointed out. Furthermore, when my package is once placed in position on its core, the edges of the package are always held straight by the core projections, so that there can be no interference between the package and the arms of the fixture. When using a fixture provided with only one projection, it is possible for the package to be shifted sidewise at the end opposite the projection, so that its edge will prevent the core from being rotated freely. My invention is, therefore, adapted to substantially eliminate the possibility of a package being improperly placed on a fixture, so as to prevent its free rotational movement when removing sheets from the package.

I claim:

In combination, a toilet paper fixture comprising a pivotally mounted package carrier provided along one edge with a pair of wedge shaped projections of different length located on opposite sides of the pivotal axis of the carrier, said carrier projections being adapted to enter notches of different depths, provided at one end of a toilet paper package, having a designated front face, the correct registration of said projections with said notches being adapted to insure the positioning of a package on said carrier with the front face presented to the user.

Dated this eighteenth day of December, 1923.

WILLARD E. SWIFT.
